UNITED STATES PATENT OFFICE

108,665

DESIGN FOR A CHAIR

Della Halbert Whitehead, Del Rio, Tex.

Application December 30, 1937, Serial No. 73,985

Term of patent 14 years

To all whom it may concern:

Be it known that Della Halbert Whitehead, a citizen of the United States, residing at Del Rio, in the county of Val Verde and State of Texas, has invented a new, original, and ornamental Design for a Chair, of which the following is a specification, reference being had to the accompanying drawing, forming part thereof.

In the drawing,
I claim:
The ornamental design for a chair as shown.

DELLA HALBERT WHITEHEAD.
